UNITED STATES PATENT OFFICE.

CHARLES WAINWRIGHT, OF ERIE, PENNSYLVANIA.

GOVERNING DEVICE FOR FLUID-COMPRESSORS.

1,081,177.

Specification of Letters Patent.

Patented Dec. 9, 1913.

Application filed May 8, 1912. Serial No. 695,889.

To all whom it may concern:

Be it known that I, CHARLES WAINWRIGHT, a citizen of the United States, residing at Erie, in the county of Erie and 5 State of Pennsylvania, have invented new and useful Improvements in Governing Devices for Fluid-Compressors, of which the following is a specification.

The invention has for its general object 10 the production of a simple, cheap and effective governing device for fluid compressors. And to this end the invention consists in a governing device arranged to operate as an inlet valve on the intake of the compressor 15 until such time as a predetermined pressure is had in the container of the compressor and then to effect constant communication between the interior of the pump or compressor apparatus and the source of fluid supply 20 for the same until such time as the container or receiver pressure falls to a point below the aforesaid predetermined or operating pressure.

Other objects will appear and be better 25 understood from that embodiment of my invention of which the following is a specification, reference being had to the accompanying drawings forming a part hereof, in which:

30 Figure 1 is a detail vertical longitudinal section with the regulating device in closed position, and the piston at or near the end of the compression stroke. Fig. 2 is a vertical cross section on the line 2—2 of Fig. 1 with 35 the controller or regulating device removed. Fig. 3 is a detail front elevation of the valve. Fig. 4 is a detail end view of the same. Fig. 5 is a front elevation of the valve seat. Fig. 6 is a vertical cross section 40 of the same. Fig. 7 is an enlarged detail section of the regulator in closed position. Fig. 8 is a view similar to Fig. 7 but showing 45 the regulator in open position. Fig. 9 is a view similar to Figs. 7 and 8 showing the means operated by the predetermined receiver pressure for holding the valve in the position shown in Fig. 8.

Referring now to the drawings *a* indicates generally the compressing or pump mechanism which is of suitable construction and arranged to be operated by a motor of any desired construction.

50 The fluid to be compressed is drawn from the atmosphere or other source of supply, 55 through a passage 5 into a chamber 6 and through a port 7 into the cylinder 8. This

drawing in of the fluid is effected by the piston 9 when the same moves to the right in Fig. 1.

A barrel or bushing 10 is confined in the 60 chamber 6 by means of plates 11—11 suitably fastened to the cylinder and arranged so as to seal the opposite ends of the chamber. The barrel or bushing is suitably held against turning in the chamber 6 and at its 65 opposite ends has enlarged circular heads 12—12 which fit into counterbores 13—13 at the opposite ends of the chamber 6. At least one of the heads 12 is detachably connected to the barrel and is removed preparatory to placing the barrel in the chamber or removing it therefrom. A port or passage 14, connects the passage 5 with the interior of the barrel 10 and a port or passage 15 establishes communication between the interior of the barrel and the chamber 6 or port 7. The port or passage 15 is controlled 70 by a valve 16 which is mounted on a horizontal pivot or pintle 17 carried by the heads 12—12 or otherwise suitably connected 75 to the barrel. The barrel is formed with a flat face or side 18 and it is in this face that the port or passage 15 is formed. The plane of the face is oblique to a line drawn vertically to the axis of the barrel when the parts 80 are arranged as shown in the drawings. With this arrangement the valve 16 extends parallel with the face or side 18 and is normally held seated or bearing on the face 18 and over the passage 15 by gravity. The 85 mass of the valve, however, is not so great as the pressure present in the passage 5 and interior of the barrel when the piston is moving to the right in Fig. 1, so that during such movement of the piston, the valve will 90 lift under the pressure in the barrel and chamber 5 so as to admit of the passage of the air or fluid into the cylinder. When the pressure in the barrel and cylinder are equalized at the end of the stroke to the right in 95 Fig. 1, the valve will close by gravity and so remain throughout the compression stroke of the piston. This action of the valve will be effected upon each reciprocation of the piston and until a predetermined pressure 100 has been attained in the receiver of the compressor.

Referring now to Fig. 9, the cylinder 19 which extends through the cylinder 8 and an opening in the rear side of the barrel 10, 110 is suitably fastened or locked to the cylinder 8, such as by a screw thread 20. A pipe

(not shown) or other suitable means, connects the cylinder 19 with any desired part of the receiver (not shown) of the compressor or with a suitable governing device (not shown) located between the cylinder and the receiver and connected to the receiver. A piston or plunger 21 located in the cylinder 20 is forced outwardly by a spring 22 which surrounds a plunger rod 23 that extends through the inner end of the cylinder and to a point adjacent to the valve 16.

Now when a predetermined pressure sufficient to overcome the resistance of the spring of the controlling device (not shown) or the spring 22, as the case may be, is obtained in the receiver of the compressor, such pressure, upon entering the cylinder 19, will project the piston rod inwardly or to the right in Fig. 9 and well into the path of movement of the valve 16. By virtue of the presence of the piston rod in the path of movement of the valve, the valve will be held in the open position as shown in Fig. 8 so that the piston on its compression stroke will force the air through passage 10, the barrel and passage 5 and into the source of fluid supply. Therefore the only resistance to the compression stroke of the piston, will be that offered by the pressure in the source of fluid supply which is seldom greater than atmospheric pressure. Thus, it will be seen that when the rod holds the valve in the position shown in Fig. 8, the cylinder will be what is known in the art as unloaded and it will remain so unloaded until such time as the receiver pressure is reduced to a point which will admit the spring 22 or the spring of the regulating device (not shown) to assume its normal position.

Although I have shown the device as associated with a single acting compressor, it will be understood that it may be used with compressors of the double acting and single or multiple stage types. It will be further observed that the valve may, if desired, be used without the unloading apparatus and may be arranged in any of the fluid pas-

sages, *i. e.* in the inlet or discharge passages or both of the compressor.

What I claim as new is:—

1. In a fluid compressor, the combination with the pump mechanism having a valve chamber and a plurality of fluid passages communicating with said valve chamber; of a barrel arranged in said chamber and having a flattened side portion and also ports communicating with said fluid passages, one of said ports being arranged in the said flattened side portion and a pivoted gravity valve for controlling the passage through the said ports. 50

2. In a fluid compressor, the combination with the pump mechanism having a valve chamber and a plurality of fluid passages communicating with said valve chamber; of a barrel arranged in said chamber and having a flattened side portion and also having ports communicating with said fluid passages, one of said ports being arranged in the said flattened side portion, and a valve pivoted to the outer surface of the barrel and arranged for controlling the passage through the said ports. 55

3. In a fluid compressor, the combination with the pump mechanism having a valve chamber and a plurality of fluid passages communicating with said valve chamber; of a barrel arranged in said chamber and having a flattened side portion and also having ports communicating with said fluid passages, one of said ports being arranged in the said flattened side portion of the barrel, a valve pivotally connected to the barrel for controlling the passage through the said ports, and means extending into the barrel and operable with a predetermined pressure in the receiver of the compressor to control the operation of said valve. 70

In testimony whereof I have affixed my signature in presence of two witnesses.

CHARLES WAINWRIGHT.
